UNITED STATES PATENT OFFICE.

ALEXANDER WEBER, OF LINCOLN, NEBRASKA, ASSIGNOR TO CUSHMAN MOTOR WORKS,
OF LINCOLN, NEBRASKA.

CARBURETER.

1,207,248.

Specification of Letters Patent.

Patented Dec. 5, 1916.

Application filed August 20, 1912. Serial No. 716,086.

To all whom it may concern:

Be it known that I, ALEXANDER WEBER, a citizen of the United States, residing at Lincoln, in the county of Lancaster and 5 State of Nebraska, have invented a new and useful Carbureter, of which the following is a specification.

This invention relates to carbureters.

Carbureters of certain type have heretofore been found objectionable because, when 10 the engine is running at a light load, there is a tendency to suck the fuel out of the nozzle and, as the current of air passing through the carbureter is not sufficiently strong to 15 carry this fuel up into the engine, the said fuel falls back into the air passage and either drips out of the bottom of the carbureter or else around the stem of the intake valve.

20 One of the objects of the present invention is to overcome this objectionable feature and to effect a considerable saving of fuel by providing means whereby fuel, after dripping back into the air passage, will be 25 sucked up to a point above the throttle valve, this action taking place repeatedly until the fuel has been broken up into particles sufficiently small to insure their passage into the motor with the air.

30 With the foregoing and other objects in view which will appear as the description proceeds, the invention resides in the combination and arrangement of parts and in the details of construction hereinafter described and claimed, it being understood 35 that changes in the precise embodiment of the invention herein disclosed, can be made within the scope of what is claimed, without departing from the spirit of the invention.

40 In the accompanying drawing, which is a section through the carbureter, the preferred form of the invention has been shown.

45 Referring to the drawing by characters of reference 1 designates the carbureter casing having an air intake 2, a mixture outlet 3, a throttle valve 4, and an air passage 5. The fuel intake nozzle is indicated at 6 and 50 is disposed as ordinarily. These parts are to be found in ordinary carbureters. The fuel nozzle 6 projects into the elbow portion of the L-shaped air passage, the throttle valve 4 being located within the upwardly 55 projecting arm of said passage.

That part of the structure constituting the present invention consists of a small tube 7 which extends within the air passage 5 from a point above the throttle valve 4 downwardly to a recess or well 8 located in 60 the lowermost portion of the air passage. Thus it will be seen that during the passage of air through the carbureter while the engine is running at a light load, fuel will be sucked, as heretofore, from the nozzle 6 and, 65 as it is too heavy to be carried by the air into the motor, a portion of the fuel will drip back into the air passage and will gravitate to the recess 8. As the tube 7 extends from this recess to a point above the 70 throttle valve 4, and as the suction above this throttle valve is quite strong, it will be seen that the fuel within the recess 8 will be sucked up through the tube 7 and discharged above the throttle valve. Should 75 any of the fuel thus elevated again drip back to the recess 8, it will a second time be conveyed upwardly through the tube 7. This movement of the fuel will continue as long as the particles are too heavy to be carried off to the motor by the air. When the fuel has ultimately been broken up into sufficiently small particles, it will be carried 80 into the motor.

It will be noted that the tube 7 is smaller 85 in diameter at its inlet end than at other points, this being due to the fact that the tube is gradually tapered toward its inlet end. Consequently the air entering the tube will travel at a greater velocity than after 90 it passes into the tube and, consequently, while the current of air passing through the inlet end of the tube will be sufficiently strong to carry upwardly the heavy fluid which has accumulated at the lower end of 95 the tube 7, the said current is not sufficiently strong to carry through the tube any but finely divided fuel. Consequently, should any particles be carried upwardly within the tube before they are sufficiently divided, 100 they will drop back into the tube to be again met by the inrushing current of air of high velocity and again carried up in the tube 7. This operation will be continued in the tube until the liquid fuel has been finely 105 divided whereupon the current in the largest portion of the tube will be sufficient to elevate the finely divided fuel into the outlet 3. Briefly considered, the present carbureter embodies a casing or body 1 having an L- 110

shaped air passage, a fuel nozzle projecting into the elbow portion of said passage, a throttle valve within the upwardly projecting arm of said passage, an air intake member 2 attached to the casing or body in communication with the lower arm of said passage, said intake member and casing having complementing depressions at their adjacent portions and at the bottom of the lower arm 10 of said passage providing a well, and a tube within said passage having its lower end curved downwardly into said well and its upper end terminating above said valve. Thus, when the member 2 is removed, access 15 is had to the lower end of the tube 7, and the parts can be readily examined and cleaned. This also facilitates the bending of the lower end of the tube to the proper point.

What is claimed is:—

20 A carbureter embodying a casing having an L-shaped air passage, a fuel nozzle pro-

jecting into the elbow portion of said passage, a throttle valve within the upwardly projecting arm of said passage, an air intake member attached to the casing in communication with the lower arm of said passage, the adjacent portions of said member and casing having complementing depressions providing a well at the bottom of said lower arm for receiving fuel, and a tube 30 within said passage having its lower end curved downwardly into said well and having its upper end terminating above said valve.

In testimony that I claim the foregoing 35 as my own, I have hereto affixed my signature in the presence of two witnesses.

ALEXANDER WEBER.
